UNITED STATES PATENT OFFICE

LOUIS COSTANZO, OF OMAHA, NEBRASKA

NECKTIE

Application filed March 19, 1929. Serial No. 348,259.

The present invention relates to improvements in neckties, and has for an object to provide an improved article of neckwear, which is ready formed and permanently 5 made up at the factory, so as not to need tying by the individual user.

Another object of the invention is to provide an improved necktie, which will possess an ornamental and becoming appearance in 10 simulation of a hand-tied necktie, but which will not be subject to wear and unsightly wrinkling as in the case of the hand-tied article.

A further object of the invention is to provide an improved article of manufacture in 15 which silk will be conserved and in which soiling and discolorization of the knot portion will be avoided by reason of the fact that the hands of the user are not required 20 to touch the knot portion as in the case where manipulation in the formation of the knot portion is involved in hand-tied neckwear.

A still further object of the invention is to provide an improved article of neckwear, 25 which is so supported and arranged with respect to the collar of the wearer that it may be conveniently and accurately centered and retained in the adjusted centered position without exhibiting any tendency to depart 30 from the position to which it is originally adjusted.

A still further object of the invention is to provide an improved article of neckwear in which the streamer body portion is short, 35 in which the knot is made from a minimum of material, and in which economy is involved in the supporting band for the tie.

With the foregoing and other objects in view, the invention will be more fully described hereinafter, and will be more particularly pointed out in the claim appended hereto.

In the drawings, wherein like symbols refer to like or corresponding parts through 45 the several views,

Figure 1 is a perspective view of an improved necktie constructed according to the present invention, and

Figure 2 is a fragmentary rear view of the 50 same.

Referring more particularly to the drawings, 10 designates the body streamer portion of the necktie, which is usually made from silk or some expensive material. According to the present invention this body portion or streamer may be of relatively short length and the knot portion is ready made or permanently formed, so that it is not dependent upon the skill of the individual wearer but will at all times present the same uniform artistic appearance and will conserve the silk material in its manufacture and enable the necktie to be applied more expeditiously. This knot portion comprises a narrow neck 11, which extends up from the streamer body 10 and is folded over at 12, providing a rear wall 13 in back of the neck portion 11, such rear wall being shown in Figure 2.

In the formation of this rear wall 13, the material is drawn down and toward one side of the neck 11, and it is thereupon folded over upon the line 14 and brought across in front of the neck 11 in a transversely extending sweeping movement with the result that a front facing 15 is formed, such facing being folded over upon the line 16 at the opposite side of the neck 11. The terminal end portion 17 extends upon the rear portion of the rear wall 13 and is affixed thereto as by the 80 stitches 18.

Now it will be noted that the upper edge 19 of the front facing 15 is disposed below the upper fold line 12 between the neck 11 and rear wall 13. The parts of the rear wall 13 and neck 11, which project above this line 19 form a casing which houses a transversely extending passage opening through both sides of the knot to receive the strip or strap 20, which preferably is of the same material and design as the necktie. The necktie is freely adjusted longitudinally on the strap 20, the strap being long enough to extend for a distance beyond both sides of the knot and to enter the wings of the collar where turned down collars are used. To the ends of the strap 20 are affixed elastic tapes 21 and 22 having respectively an eye 23 and a hook 24 by which the tapes may be secured together at the back of the neck. Included 100

with one tape, as for instance the tape 22 is an adjusting slide 25 for the purpose of lengthening or shortening the tape and consequently the entire band composed of the tapes and the strap 20.

If desired a quantity of padding 26 may be inserted within the knot portion between the neck 11 and rear wall 13, the space therebetween being open at the bottom at the rear side of the necktie, but such space being narrower at its lower open end than at its upper portion, whereby the padding 26 may be made to conform to this contour of pocket, so as to be retained against falling out of the same. The padding may be of cheaper silk or some other material which will give bulk to the knot and imitate the tied appearance of the same.

In practice, the arrangement shown in Figure 1 is particularly useful in connection with a "turn over" or "lay-down" collar, that is a collar having two upstanding vertical portions which is open at its front. The adjustment of the slide 25 is first made so that the elastic tapes 21 and 22 encircle the collar and in securing the fastening means 23 and 24 the tapes are put under tension which will hold the tapes and the strap 20 tightly and snugly about the collar, and which will therefore gather the necktie in a proper taut position against the collar. The necktie may be then adjusted laterally along the strap 20 to bring it to a selected central position in order to present the proper ornamental dressed appearance.

It will be noted that such adjustment of the knot upon the strap 20 may be made without regard to the construction or adjustment of the tapes 21 and 22 and of the fastening means 23 and 24.

The ends of the strap 20 are tucked under the flaps of the collar and are out of sight and, of course, the elastic tapes 21 and 22 are concealed by the collar from view.

It will be understood that in instances where a "lay down" collar is not used and the necktie is to be attached to a "stand-up" collar the elastic tapes 21 and 22 may be dispensed with and the strap 20 may extend all the way round to the hook and eye 23 and 24 at the rear. An elastic insert will preferably be included in such strap 20 for creating the desired pressure of the band about the collar. It will be noted from the foregoing that the

expensive silk material utilized in the manufacture of neckties may be conserved, since not so much material is involved in the knot portion, and where the knot portion is permanently made at the factory the stremper body 10 need not be so long, but is considerably shorter and no additional stremper is necessary.

I do not wish to be restricted to the size, form, and proportions of the various parts, and obviously changes could be made in the

construction herein described without departing from the spirit of the invention, it being only necessary that such changes fall within the scope of the appended claim.

What is claimed is:

An improved necktie comprising a body portion, a knot portion composed of a neck at the upper part of the body portion, a rear wall connected with the neck and lying behind the same, a front facing connected with the rear wall at one side and lying transversely across and in front of the neck with its upper edge spaced below the upper connected edges of the neck and rear wall, and a terminal end portion connected at the other side with the facing lying behind the rear wall and connected thereto, said neck and rear wall forming above the facing a transverse slip passage, and supporting means slidable through said passage.

In testimony whereof, I have affixed my signature.

LOUIS COSTANZO.
